US00D900805S

(12) **United States Design Patent** (10) **Patent No.:** **US D900,805 S**
McWilliam et al. (45) **Date of Patent:** **** Nov. 3, 2020**

(54) **ELECTRONIC DEVICE**

(71) Applicant: **Amazon Technologies, Inc.**, Seattle, WA (US)

(72) Inventors: **Giles David Matthew McWilliam**, San Francisco, CA (US); **Christopher Green**, San Francisco, CA (US); **Monica Liane Mecchella**, San Francisco, CA (US)

(73) Assignee: **Amazon Technologies, Inc.**, Seattle, WA (US)

(**) Term: **15 Years**

(21) Appl. No.: **29/724,761**

(22) Filed: **Feb. 19, 2020**

Related U.S. Application Data

(62) Division of application No. 29/704,390, filed on Sep. 4, 2019, now Pat. No. Des. 879,152, which is a division of application No. 29/675,982, filed on Jan. 7, 2019, now Pat. No. Des. 865,003, which is a division of application No. 29/615,518, filed on Aug. 29, 2017, now Pat. No. Des. 841,693.

CLAIM

The ornamental design for an electronic device, as shown and described.

DESCRIPTION

FIG. 1 is a top perspective view of an electronic device; FIG. 2 is a bottom perspective view thereof;

FIG. 3 is a back view thereof;

FIG. 4 is a front view thereof;

FIG. 5 is a left-side view thereof;

FIG. 6 is a right-side view thereof;

FIG. 7 is a top view thereof; and,

FIG. 8 is a bottom view thereof.

The broken lines represent features of the electronic device that form no part of the claimed design.

1 Claim, 8 Drawing Sheets
